CLAIM

The ornamental design for a microwave antenna and electronics housing assembly, as shown and described.

DESCRIPTION

FIG. 1 is a perspective view of a microwave antenna and electronics housing assembly showing our new invention;
FIG. 2 is a right side view of the invention;
FIG. 3 is a front elevation view of the invention;
FIG. 4 is top plan view of the invention;
FIG. 5 is a rear elevation view of the invention;
FIG. 6 is a left side view of the invention; and,
FIG. 7 is a bottom plan view of the invention.
